(57) **CLAIM**

The ornamental design for a water floatation device, as shown and described.

DESCRIPTION

FIG. 1 is a front perspective view of a water floatation device showing, in particular, the ornamental design thereof.

FIG. 2 is a side view of the water floatation device of FIG. 1.

FIG. 3 is a top view of the water floatation device of FIG. 1.

FIG. 4 is a bottom view of the water floatation device of FIG. 1.

FIG. 5 is a front view of the water floatation device of FIG. 1; and,

FIG. 6 is a rear view of the water floatation device of FIG. 1.

The broken lines illustrate portions of the water floatation device that form no part of the claimed design.

1 Claim, 3 Drawing Sheets
